CIGARETTE MAKING MACHINE

Maurice X. C. Weinberger, Brooklyn, N. Y., assignor to Self Extinguishing Cigarette Corporation, New York, N. Y., a corporation of New York

Application March 8, 1934, Serial No. 714,586

15 Claims. (Cl. 131—39)

This invention relates generally to cigarette-making machines, and has particular reference to machines for use in the manufacture of cigarettes of the self-extinguishing type, wherein the wrapper, according to the invention to which my co-pending patent application Serial No. 664,888, filed April 7, 1933, is directed, is provided immediately prior to the tobacco-filling and cigarette-rolling operation with a transverse film-like coating of suitable agglutinating substance, to which certain particles of the tobacco adhere during the filling operation so as to provide in the finished cigarette an annular, combustion-retarding band of tobacco particles, in union with the inner face of the cigarette wrapper intermediate the ends thereof.

Important objects of the present invention are to provide a machine for use in making cigarettes of the above general character which is simple in construction, reliable in operation, efficient in use and which is under such automatic control that possible damage to either the machine in its entirety or to any part or parts thereof is positively averted should the traveling web-like wrapper paper break under operating conditions.

Other objects and advantages of the invention will become apparent from the following description, taken in connection with the accompanying drawings, in which—

Fig. 1 is a fragmental view, partly in elevation and partly in section, of a cigarette-making machine embodying the invention; Fig. 2 is a plan view of the machine as viewed from above in Fig. 1; Fig. 3 is an elevation of the machine, as viewed from the rear in Fig. 1; Fig. 4 is a horizontal, sectional view taken on line 4—4 of Fig. 1; Fig. 5 is a central, vertical, sectional view of the machine, certain elements being shown in elevation; Fig. 6 is an end elevation of the machine, as viewed from the left in Figs. 1 and 5; Fig. 7 is a vertical, sectional view taken on line 7—7 of Fig. 5 and Fig. 8 is a sectional view taken on line 8—8 of Fig. 1.

Inasmuch as the present invention is adapted for use in connection with standard types of cigarette-making machines, wherein the tobacco filler is fed from a hopper onto a traveling web-like wrapper paper, which is thereafter folded around the filler and then sealed at its meeting margins, it is deemed unnecessary, for a complete understanding of the present invention, to refer to any details of such standard machines other than the machine frame 10, tobacco hopper 11, main driving gear 12, printing drum 14, and idler roller 15, about which passes the web-like wrapper paper 16

as it leaves the printing drum to which it is supplied from a suitable source, not shown.

Although the device embodying the present invention may be constructed as a unit capable of being attached to or detached from a standard type of cigarette-making machine, it is herein illustrated as incorporated in such machine as a permanent part thereof by providing the machine frame 10 with an integral frame member 17, on which are supported the various elements about which the present invention centers. Journalled in the frame member 17, is a main shaft 18, on the rearwardly projecting end of which is detachably supported a gear assembly 20, by which that shaft is operatively connected to the driving gear 12. The gear assembly 20 includes a gear-carrying arm 21, which is removably journalled on the rear end of the shaft 18, and is provided with a trunnion 22, on which is carried a gear 24, adapted to mesh with a gear 25, removably secured to the shaft 18 by a gear-retaining nut 26. In order that the gear-assembly 20 may be locked in such position that the gear 24 will properly engage the gear 12 and thereby rotate the shaft 18 in a counter-clockwise direction as viewed in that figure, the arm 21 is provided at its outer end with an arcuate slot 27, adapted for the reception of a screw-threaded stud 28, carried by the frame member 17 and provided with a clamp nut 30, the arc of the slot 27 being struck from the center of the shaft 18 on which the arm 21 is pivotally hung. From the foregoing description of the gear assembly 20, it will be understood that the driving connection which that assembly is adapted to afford between the gear 12 and the shaft 18 may be severed by releasing the clamp nut 30 and swinging the gear-carrying arm 21 a sufficient distance in a clockwise direction, as viewed in Fig. 3, to disconnect the gear 24 from the gear 12. Moreover, it will be understood that the gear assembly, including the gear 25, may, if desired for any reason, be easily removed from the general organization of elements entering into the invention upon removing the clamp nut 30 from the stud 28 and detaching the gear-retaining nut 26 from the shaft 18.

Removably secured to the shaft 18, is a feed roller 31, of suitable material such as brass, carrying at one end thereof a gear 32, which is also removable from that shaft. Pivotally and removably supported on the shaft 18, is a bell crank lever 34, within one arm 35 of which is removably journalled one end of a shaft 36, the other end of such shaft being removably jour-

nalled in a link 37, pivotally supported on the outer end of the shaft 18. To the shaft 36, is connected a gear 38, which is maintained, under all conditions of operation, in driving engagement with the gear 32. Intermediate the gear 38 and the link 31, the shaft 36 is provided with a transfer roller 40, of suitable material such as rubber, which engages the peripheral surface of the roller 31, the peripheral speeds of which rollers are identical due to the fact that they are of the same diameter and the ratio of the gears 32 and 38 which operatively connect them is one-to-one. Carried by the frame member 17, is a trunnion 41, on which is removably journaled a bearing sleeve 42, between the reduced portion 44 and the hub portion 45 of which is formed a shoulder 46. This sleeve 42 is provided on its hub portion 45 with a gear 47, which is of the same diameter as the gear 38 with which it is adapted to engage. Removably carried by the reduced portion 44 of the sleeve 42, is a pick-up roller 48, which is adapted to be held in driving engagement with the shoulder of the sleeve by a nut 50, carried by the outer screw-threaded end of the reduced portion 44 of the sleeve. This pick-up roller is provided with a pair of oppositely disposed and radially projecting ribs 51, the length of each of which is somewhat less than the width of the wrapper paper 16, and the opposite side faces of which are slightly undercut, as shown in Figs. 1 and 5, and the outer surfaces of which conform in curvature to the peripheral curvature of the transfer roller 40 with which they are adapted to engage, it being noted that the diametrical distance between the faces of the ribs 51 is equal to the diameter of the transfer roller. Carried by the pick-up roller 48, are a pair of oppositely disposed knives 52, which are arranged intermediate the ribs 51 at opposite sides of a plane passing through the axis of the roller 48 and longitudinally bisecting the ribs 51, it being noted that the outer or cutting edges of the knives 52 are disposed at a slightly shorter distance from the center of rotation of the roller 48 than are the peripheral surfaces of the rib 51 so that they will not contact with the peripheral surface of the roller 40 under any conditions of operation.

Carried by the frame member 17, is a yieldable bearing block 54, which is urged by a compression spring 55 toward the pick-up roller 48, the extent of movement of the block toward such roller being limited by an adjustable stop 56, in the form of a lag screw mounted in the frame member 17 and positioned in the path of movement of the block. Although the bearing block 54 may be movably supported in various ways, it is herein shown as disposed within an opening 57, provided in the frame member, opposite parallel side walls 58 of which are shaped to provide guide ribs 60, which conform to and are received by V-shaped grooves 61, provided in the parallel side faces of the block. In order that the block 54 may be easily introduced into the opening 57 and easily positioned on the guide ribs 60, the opening, at one end thereof, is sufficiently large to receive the guide block so that it may be moved onto the guide ribs 60, thus allowing the compression spring 55 to be inserted in the opening 57 where it is held under compression under all conditions of operation with one of its ends abutting the end wall of the opening and its other end abutting one end of the guide block, the block being provided with a lug 62 about which the block-engaging end of the spring is disposed so

as to prevent the spring from being unduly dislodged. Carried by the bearing block 54, is a trunnion 64, on which is detachably journaled a contact roller 65. Substantially directly beneath the contact roller 65, there is disposed a guide roller 66 which is mounted on a stub shaft 67, carried by the frame member 17.

Suitably located on the frame member 17, is a control device 68, which includes a trip roller 70, disposed intermediate the contact roller 65 and 10 a supporting roller 71, which is associated with the feed hopper 11 and over which the wrapper paper 16 travels as it is drawn along beneath the hopper during the tobacco-filling operation in a substantially taut condition. The trip roller 70 15 is journaled in the upper or yoke-like end 72 of a vertically disposed rod 74, which is adapted for vertical movement within a pair of guides 75, attached to the frame member 17. The lower end of the vertically movable rod 74 is provided 20 with a pin 76, adapted to operate within an elongated slot 77, provided in one arm 78 of a bell crank lever 80, pivotally connected to the frame member 17, the other arm 81 of the bell crank lever being provided with means, such as a weight 25 82, by which the bell crank lever may be moved in a counter-clockwise direction, as viewed in Fig. 1, under certain conditions of operation, as for example when the wrapper paper 16 accidentally breaks and consequently fails to maintain the trip 30 roller 70 depressed.

Associated with the control device 68, is an electric switch 84, which includes a stationary contact 85, suitably supported by and insulated from the frame member 17, and a movable contact 86, 35 carried by and suitably insulated from the arm 81 of the bell crank lever 80. These contacts are maintained open so long as the trip roller 70 is maintained in engagement with the more or less taut wrapper paper 16 as it passes from the 40 contact roller 65 and progressively presents itself in position beneath the hopper 11 to receive the tobacco filler therefrom. If the wrapper paper 16 breaks so that it can no longer maintain the trip roller 70 depressed, the operation of the control device, acting under the influence of the weight 82, is such as to cause the contacts 85 and 86 to engage each other, and thereby close the circuit C of a solenoid 87, suitably supported on the frame member 17, the core 88 of which solenoid is 50 pivotally connected to the depending arm 35' of the bell crank lever 34. This bell-crank-lever arm 35' is normally held in its position shown in Fig. 1 by a tension spring 90, one end of which is suitably connected to that arm and the other end of 55 which is suitably anchored to the frame member 17. In order that the bell crank lever 34 may be so adjusted as to effect a proper normal contact relation between the periphery of the transfer roller 40 and the arcuate surface of the ribs 51 of 60 the pick-up roller 48, an adjustable abutment 91 is provided. This abutment includes a longitudinally adjustable screw 92 in intimate engagement with which the bell-crank-lever arm 35' is normally held by the spring 90, the screw 92 being 65 carried by a lug 94 supported by the frame member 17.

From the foregoing description of the control device 68, and the relation of the solenoid 87 to the bell-crank-lever arm 35', it will be apparent 70 that as soon as the switch 84 is closed, the solenoid 87 will be energized to swing the bell crank lever 34 in a counter-clockwise direction, as viewed in Fig. 1, thereby disengaging the gear 38 from the gear 47 and simultaneously moving the transfer 75

roller 40 well out of its normal position of contact with the arcuate surface of the ribs 51 without disturbing the contact relation between the feed roller 31 and the transfer roller 40 or the driving engagement between their associated gears 32 and 38. In order to guard against the possibility of fouling the rollers 31 and 40, as for example upon breakage of the wrapper paper 16 when a loose end of such wrapper paper might be picked up by the transfer roller 40 and wound thereabout, a suitable shield 95 is provided. This shield is removably supported on the frame member 17 by a pin 96 carried thereby, and is so shaped as to partially encircle the roller 40 at a sufficient distance to permit the roller to move unobstructedly away from the pick-up roller 48 under the influence of the solenoid 87.

Removably supported on the frame member 17, is a reservoir unit 97, adapted to carry a supply of suitable agglutinating substance. This reservoir unit 97 includes a pair of side plates 98, corresponding ends of which are shaped to snugly fit within a pair of annular grooves 100, provided in the feed roller 31 adjacent opposite ends thereof, the upper margins of the walls being extended past the feed roller, as shown in Figs. 1 and 5, to a position in close proximity to the pick-up roller 48. The side plates 98 are connected together by a pair of transverse tie members 101, on which is slidably mounted a gate 102, the forward end of which, as shown in Fig. 5, is bevelled and is adapted to be maintained in such spaced relation to the feed roller 31 as to insure the proper quantity of agglutinating material being carried from the reservoir unit 97 on the peripheral surface of the feed roller. In order that the position of the bevelled end of the gate 102 may be varied with respect to the peripheral surface of the feed roller 31 as occasions may require, the opposite end of the gate is swivelled to an adjusting screw 104, which is provided at its outer end with a thumb wheel 105 and is supported intermediate its ends within a screw-threaded lug-like extension 106, carried by one of the side plates 98 of the reservoir unit 97. The gate 102 serves as the bottom wall of a hopper 107, which includes portions of the side plates 98, a pair of transverse wall sections 108 and an inclined wall section 110, the upper end of which is connected to one of the wall sections 108 and the lower end of which is disposed in close proximity to the upper surface of the gate 102. Upon the hopper 107, is carried a removable receptacle 111, having an open upper end and adapted for the reception of a suitable agglutinating material 112, on which is buoyantly supported a follower 114, which serves to protect the agglutinating material from undue contact with the atmosphere and functions, because of its weight, to insure proper transfer of the agglutinating material 112, on which is carried from the hopper 107. Journalled in the side plates 98 of the reservoir unit 97, is a transverse shaft 115, which carries at one end a gear 116 adapted to engage the gear 32 when the unit 97 is positioned as shown in Figs. 1 and 5. The shaft 115 is provided intermediate the side plates 98 with one or more propeller-like agitators 117, which serve to act on the agglutinating material as to impart to it a proper consistency and urge it into contact with the feed roller 31, by which it is carried from the hopper 107 through the space afforded between that roller and the bevelled end of the gate 102. As the agglutinating material is carried from the unit 97 on the face of the feed roller 31, it is delivered to the transfer roller 40,

from which the ribs 51 of the pick-up roller 48 derive a supply of that material to be delivered to the wrapper paper 16 as it passes over the contact roller 65. In order to clean the arcuate surfaces of the ribs 51 of any excess material that may remain thereon prior to their being presented to the transfer roller 40 for a fresh supply, there is provided intermediate the side plates 98 of the reservoir unit 97 a scraper 118, one end of which is shaped to present a scraping edge, which is so adjusted with respect to the arcuate surfaces of the ribs 51 as to effectively remove excess material therefrom. Any material so removed from the ribs 51 is delivered along the upper surface of the scraper 118 and onto a removable closure 120, suitably supported intermediate the side plates 98 at a sufficient distance from the adjacent wall section 108 to provide ample space, as shown at 121, through which material delivered to the closure from the scraper may pass into the hopper 107 at a point in front of the propeller-like agitators 117 which re-condition the reclaimed material for use by mixing it with fresh material supplied from the receptacle 111.

Assuming that the machine is conditioned for use, as shown in the drawings, its operation is as follows: As the wrapper paper 16 passes from the printing drum 14 over the idler roller 15, guide roller 66, contact roller 65 and thence along its path of travel over the trip roller 70, the agglutinating material 112, as it is fed from the hopper 107 into contact with the peripheral surface of the feed roller 31, is delivered, in the form of a thin ribbon-like film, onto the transfer roller 40, from which quantities are picked up by the ribs 51 as they move into and out of pick-up relation to the peripheral surface of the transfer roller. From the ribs 51, the material is transferred to the wrapper paper 16 as it passes over the contact roller 65, any excess material remaining on the surfaces of the ribs pursuant to each transfer of material to the wrapper paper being removed by the scraper 118 and directed back into the reservoir unit 97. It will be understood that the transverse film-like coatings of agglutinating substance, with which the wrapper paper 16 is thus provided, are carried on the tobacco-receiving face of the wrapper paper, with the result that, as the tobacco-filling operation is carried out from the hopper 11, certain particles of tobacco will adhere to the coatings so as to provide an annular, combustion-retarding band of tobacco particles, in union with the inner face of the wrapper of each cigarette severed, according to well-known practice, from the pencil-like cigarette structure as it emerges from the discharge end, not shown, of the machine. Here it is to be noted that the arcuate distance from center to center of the ribs 51 of the pick-up roller 48 corresponds to the linear distance from the longitudinal center line of each transverse coating on the wrapper paper 16 to the corresponding center line of the next adjacent coating, and that such arcuate distance therefore corresponds to the over-all length of the individual cigarettes, when the cut-off mechanism, not shown, is timed to sever the pencil-like cigarette structure at definite intervals and at definite distances from each annular, combustion-retarding band produced according to the present invention.

Should the wrapper paper 16 accidentally or otherwise become severed during the operation of the machine, the trip roller 70, in the absence of such wrapper paper, is permitted to move up-

wardly under the influence of the weight 82, with the result that the switch 84 is closed, the solenoid 87 is energized, the bell crank lever 34 is moved in a counter-clockwise direction, as viewed in Fig. 1, the gear 38 is disengaged from the gear 47, and the transfer roller 40 is moved out of rib-engaging relation to the pick-up roller 48. Should the break in the wrapper paper 16 occur at such a point as to permit one of the ribs 51, due to the presence of a quantity of agglutinating material thereon, to adhere to a free end of the wrapper paper and carry it in a clockwise direction over the pick-up roller, such paper will be subjected to sufficient tension to cause the knife 52 to sever it at a point following that rib, the portion so severed being then removed by the scraper 118 without fouling or otherwise damaging the machine. Such severing of the wrapper paper 16 and removal of the severed portion will, of course, occur as many times as a union is thus effected between the wrapper paper and the pick-up roller 48 before that roller comes to rest pursuant to the automatic operation of the solenoid 87. Should the wrapper paper 16, for any reason, present a free end to the transfer roller 40, such free end is definitely prevented, due to the presence of the guard 95, from becoming attached to the surface of that roller with a consequent winding thereabout of the wrapper paper.

Although the various elements entering into the present invention are accurately timed or synchronized, by resorting for example to proper gear ratios, roller diameters and so on, provision is made for advancing or retarding the points of application of the agglutinating material to the wrapper paper 16 should such points of application tend to creep lengthwise of the paper in one direction or another, for example with respect to any printing that may be applied to the wrapper paper with the aid of the printing drum 14 in a manner well understood in the art. Such advancing or retarding of the points of application of the agglutinating material to the wrapper paper 16 is made possible by reason of the fact that the pick-up roller 48 can be readily adjusted to a proper advanced or a retarded position on its sleeve 42, as conditions may require, without disturbing the position of the gear 47 by which that shaft is rotated and regardless of whether the required correction with respect to points of application of the agglutinating material to the wrapper paper is large or small.

Although only one form of the invention is herein shown and described, it will be understood that various changes may be made without departing from the spirit of the invention or the scope of the following claims.

What is claimed is:

1. In a cigarette-making machine of the type wherein a tobacco-filling operation is carried out with respect to a moving web-like wrapper to be folded around the filler and sealed at its meeting margins, a wrapper-treating device for applying an agglutinating substance to the tobacco-contacting side of the wrapper prior to the tobacco-filling operation and comprising a reservoir adapted for the reception of a quantity of agglutinating substance, and means for transferring the agglutinating substance from said reservoir to said wrapper at intervals spaced from each other along the length of the wrapper.

2. In a cigarette-making machine of the type wherein a tobacco-filling operation is carried out with respect to a moving web-like wrapper to be folded around the filler and sealed at its meet-

ing margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each other along the length of the wrapper, and control means cooperating with said wrapper and operable upon the occurrence of a break in the same to render said transfer means inoperative.

3. In a cigarette-making machine of the type wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, and means for transferring the agglutinating substance from said reservoir to said wrapper at intervals spaced from each other along the length of the wrapper and including a feed roller, a transfer roller engaging said feed roller and a pick-up roller having a radial rib adapted to receive an agglutinating substance from said transfer roller and deliver it to said wrapper.

4. In a cigarette-making machine of the type wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each other along the length of the wrapper and including a feed roller, a transfer roller engaging said feed roller and a pick-up roller having a radial rib adapted to receive an agglutinating substance from said transfer roller and deliver it to said wrapper, and control means cooperating with said wrapper and operable upon the occurrence of a break in the same to move said transfer roller away from said pick-up roller and out of rib-engaging position.

5. In a cigarette-making machine of the type wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each other along the length of the wrapper, and including a feed roller, a transfer roller engaging said feed roller, means supporting said transfer roller for swinging movement about the axis of said feed roller, a pick-up roller having a radial rib adapted to receive an agglutinating substance from said transfer roller and deliver it to said wrapper, and control means operable upon the occurrence of a break in said wrapper to move said transfer roller away from said pick-up roller and out of rib-engaging position.

6. In a cigarette-making machine of the type wherein a tobacco-filling operation is carried out with respect to a moving web-like wrapper to be

- folded around the filler and sealed at its meeting margins, a wrapper-treating device for applying an agglutinating substance to the wrapper prior to the tobacco-filling operation and comprising 5 a reservoir adapted for the reception of a quantity of agglutinating substance, means for transferring the agglutinating substance from said reservoir to said wrapper at intervals spaced from each other along the length of the wrapper, and 10 cutting means associated with said transfer means for severing the wrapper into lengths upon accidental union being established between said wrapper and said transfer means.
7. In a cigarette-making machine of the type 15 wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced 20 from each other along the length of the wrapper and including a feed roller, a transfer roller engaging said feed roller and a pick-up roller having a radial rib adapted to receive an agglutinating substance from said transfer roller and deliver it to said wrapper, and cutting means carried by said pick-up roller and adapted to sever said wrapper into lengths upon accidental union being established between said wrapper and said pick-up roller.
- 30 8. In a cigarette-making machine of the type 25 wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced 30 from each other along the length of the wrapper and including a feed roller, a gear associated with said feed roller, a transfer roller engaging said feed roller, a gear associated with said transfer roller, means supporting said transfer roller for swinging movement about the axis of said feed roller while maintaining said gears in a meshing relation, a pick-up roller having a radial rib adapted to receive an agglutinating substance from said transfer roller and deliver it to said wrapper, a gear associated with said pick-up roller and adapted to mesh with the second-mentioned gear, and control means operable upon the occurrence of a break in said wrapper to move said transfer roller away from said pick-up roller and out of rib-engaging position and to disengage the third and second-named gears without disturbing the meshing relation between said first and second-named gears.
- 35 9. In a cigarette-making machine of the type 35 wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each other along the length of the wrapper and including a feed roller, a transfer roller engaging said feed roller and a pick-up roller having a radial rib adapted to receive an agglutinating substance from said transfer roller and deliver it to said wrapper at intervals spaced from each other along the length of the wrapper; and cutting means carried by said pick-up roller intermediate said ribs and adapted to sever said wrapper into lengths 10 upon accidental union being established between said wrapper and said ribs tending to result in the wrapper being wound around the pick-up roller during rotation of the same.
10. In a cigarette-making machine of the type 15 wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced 20 from each other along the length of the wrapper and including a feed roller, a transfer roller engaging said feed roller and a pick-up roller having a radial rib adapted to receive an agglutinating substance from said transfer roller and deliver it to said wrapper, and means for removing excess agglutinating substance from said rib and for delivering such removed excess to a point remote to said pick-up roller.
11. In a cigarette-making machine of the type 35 wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each 40 other along the length of the wrapper and including a feed roller, a transfer roller engaging said feed roller and a pick-up roller having a radial rib adapted to receive an agglutinating substance from said transfer roller and deliver it to said wrapper, control means cooperating with said wrapper and operable upon the occurrence of a break in the same to move said transfer roller away from said pick-up roller and out of rib-engaging position and including a solenoid 45 having an operative connection with said transfer roller, a normally open switch adapted for connection in the circuit of said solenoid, pressure means adapted to engage said wrapper when said wrapper is intact and to then maintain said 50 switch in open-circuit condition, and means rendered effective upon release of said pressure means to move said switch to closed-circuit position.
12. In a cigarette-making machine of the type 60 wherein a tobacco-filling operation is carried out with respect to a moving web-like wrapper to be folded around the filler and sealed at its meeting margins, a wrapper-treating device for applying an agglutinating substance to the tobacco-contacting sides of the wrapper prior to the tobacco-filling operation and comprising a reservoir adapted for the reception of a quantity of agglutinating substance, means for transferring the agglutinating substance from said reservoir to said wrapper at intervals spaced from each other 70
- 75 75

along the length of the wrapper, and means for yieldably supporting the wrapper at a point in its travel adjacent said transferring means and cooperating with said transferring means to facilitate application of the agglutinating substance to the wrapper.

13. In a cigarette-making machine of the type wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each other along the length of the wrapper and including a feed roller, a transfer roller engaging said feed roller and a pick-up roller having a radial rib adapted to receive an agglutinating substance from said transfer roller and deliver it to said wrapper, and yieldably supported means disposed adjacent said pick-up roller for supporting said wrapper in position to be there engaged during its travel by said rib incident to the delivery of agglutinating substance by that rib to the wrapper.

14. In a cigarette-making machine of the type wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance

from said reservoir to said wrapper at intervals spaced from each other along the length of the wrapper and including a feed roller, a transfer roller engaging said feed roller and a pick-up roller having a radial rib adapted to receive an agglutinating substance from said transfer roller and deliver it to said wrapper, and yieldably supported means disposed adjacent said pick-up roller for supporting said wrapper in position to be there engaged during its travel by said rib incident to the delivery of agglutinating substance by that rib to the wrapper, said yieldably supported means including a movable bearing block, a spring having one end maintained in supporting relation to said block, a shaft carried by and movable with said block, and a roller journaled on said shaft and over which said wrapper is adapted to pass.

15. In a cigarette-making machine of the type wherein a tobacco-filling operation is carried out with respect to a moving web-like wrapper to be folded around the filler and sealed at its meeting margins, a wrapper-treating device for applying an agglutinating substance to the wrapper prior to the tobacco-filling operation and comprising a reservoir adapted for the reception of a quantity of agglutinating substance, means for transferring the agglutinating substance from said reservoir to said wrapper at intervals spaced from each other along the length of the wrapper and including a feed roller, a transfer roller engaging said feed roller and a pick-up roller having a radial rib adapted to receive an agglutinating substance from said transfer roller and deliver it to said wrapper, and agitating means adapted to act on the agglutinating substance en masse and to deliver it to said feed roller.

MAURICE X. C. WEINBERGER.
